UNITED STATES PATENT OFFICE.

JAMES J. STEWART, OF MARSHALLTOWN, IOWA.

DESIGN FOR A STOVE-BASE.

45,029.

Specification for Design.

Patented Dec. 9, 1913.

Application filed September 17, 1913. Serial No. 790,369. Term of patent 7 years.

To all whom it may concern:

Be it known that I, JAMES J. STEWART, a citizen of the United States, residing at Marshalltown, in the county of Marshall and State of Iowa, have invented a new, original, and ornamental Design for Stove-Bases, of which the following is a specification, reference being had to the accompanying drawing, forming part thereof.

The figure is a perspective view of my stove base, showing the new design.

The stove base is designed to be placed

under the body of the stove and to be used as a substitute for the ordinary stove legs which are very fragile and frequently cause annoyance by breakage.

I claim:

The ornamental design for a stove base, as shown.

JAMES J. STEWART.
